**CONVERTIBLE OIL FEED PLUG AND VISIBLE
OIL LEVEL AND RESERVOIR KIT**
George F. McKenney, Turner Road, Auburn, Maine
Filed Oct. 25, 1961, Ser. No. 147,693
1 Claim. (Cl. 73—303)

This invention relates to a novel convertible oil feed plug usable with a visible oil level and reservoir kit for use with usual four-cycle gasoline engines.

The usual four-cycle gasoline driven motor which supplies power for home lawn mowers, snow blowers, or the like depends for its lubrication upon a separate oil receptacle to which oil may be added through an opening usually closed by a plug. The plug may or may not have a dip stick attached depending upon the depth of the oil receptacle. Among the usual operators of such motors are found to be housewives and teenagers who are often times not sufficiently aware of the needs of the four-cycle motors to be alerted to check the oil receptacles of such motors to make certain that there is sufficient oil for proper operation without damage to the part.

According to the present invention a convertible oil feed plug is provided with a visible oil level and reservoir kit which is adapted to be attached to existing four-cycle gasoline motors and provide a visible warning as to when oil must be added to such engines. The kit also serves to provide a reservoir to additional oil for the lubrication of such motors.

Although such novel features as are believed to be characteristic of the invention and are pointed out in the claim, the invention and the manner in which it may be carried out, may be further understood by reference to the description following and the accompanying drawings.

FIGURE 1 is a perspective of a motor driven lawn mower showing a convertible oil feed plug and visible oil level and reservoir kit attached.

FIGURE 2 is a front elevation of a convertible oil feed plug and visible oil level and reservoir kit of the present invention.

FIGURE 3 is a detail of a convertible plug of the present invention.

FIGURE 4 is a cross section view of a convertible plug of the present invention in a shallow oil receptacle four-cycle motor.

FIGURE 5 is a cross section view of a convertible plug of the present invention in a deep oil receptacle of a four-cycle motor.

Referring now to the figures in greater detail, where like reference numbers denote like parts in the various figures.

In FIG. 1 a visible oil level and reservoir kit 1 and convertible plug 2 of the present invention is shown attached to a four-cycle motor powered lawn mower. The visible oil level and reservoir kit 1 comprises a convertible plug 2, an oil line 3, a transparent or translucent reservoir container 4, a clamp 5 adapted to attach the container 4 to an appropriate point on a motorized device where it can be seen. As shown in FIG. 2 a stiff tube 6 for use in deep base oil reservoir four-cycle gasoline motors extends from the convertible plug 2.

The convertible plug 2 is provided with a hollow length 7 which opens into an enlarged exterior 8 shown in FIGURES 3, 4 and 5 defining a conical shape. The enlarged exterior 8 has an inset 9 communicating with it which is part of the hollow length 7. The inset 9 is adapted to hold the stiff tube 6. The inset 9 ends at a wall 10 which communicates with a further inset 11 which is part of the hollow length 7. The inset 11 is adapted to receive the oil line 3.

The convertible plug 2 is generally of a standard size since most oil reservoir plugs for four-cycle motors for

2

lawn mowers and the like are of the same diameter. The stiff tube 6 is cut off at an angle forming a nib 12.

The visible oil level and reservoir kit 1 may come provided with the oil line 3 attached in the inset 11 of the convertible plug 2 by being cemented or otherwise attached with the end of the oil line 3 terminating at the removable cap 13 of the container 4 or the kit may be provided with the individual parts unattached to the convertible plug 2.

In operation in a shallow reservoir four-cycle gasoline motor the original plug of the four-cycle motor is replaced by the convertible plug 2, the container 4 is attached to an appropriate point where an operator of the four-cycle engine might see the container 4. The clamp 5 holds the container 4 in its selected location. The clamp 5 is provided with a first gripping area 14 adapted to hold the clamp 5 with container 4 where the clamp 5 is affixed. The clamp 5 is provided with a second resilient gripping area 15 adapted to removably hold the container 4 to facilitate installation and filling of the container 4. When the oil line 3 is not already attached, once a location for the container 4 and clamp 5 has been selected the oil line 3 may then be extended from the container 4 to the convertible plug 2 in the oil reservoir of the four-cycle motor, excess length of the oil line 3 may then be cut off and the oil line 3 is inserted and/or cemented in the inset 11.

A shoulder 16, formed by the junction of the enlarged exterior 8 and bottom of the convertible plug 2, when fully inserted in the opening of a shallow oil receptacle of a four-cycle gasoline motor is submerged in the lubricant oil of the motor. The container 4 is filled with oil and the cap 13 with the attached oil line 3 closed. The container 4 is engaged in the second gripping area 15 of the clamp 5 in inverted position allowing the oil level to be visible and the reservoir to function.

When the oil level of the four-cycle gasoline motor drops below the level of the shoulder 16, oil seeps into the motor oil receptacle from the container 4, maintaining lubrication in the motor. The enlarged exterior 8 of the hollow length 7 acts to assist the oil flow and prevents the viscosity of the oil from holding back seepage into the oil receptacle of the motor because of the small opening of the hollow length 7. The enlarged exterior 8 also facilitates air passing into the oil line 3 to the container 4 allowing the oil to seep.

A plastic known by the trademark Derlin has been found effective as one of the substances the convertible plug 2 may be constructed of. The container 4 may be provided with markings such as "full" and "empty" as warnings as to when oil in the motor receptacle or in the container 4 ought to be added. The container 4 may be provided with a second replaceable opening to allow for its filling without removal of the cap 13. The cap 13 and oil lines 3 may be unitary when another closure of the container is provided.

Where a convertible plug 2 and visible oil level and reservoir kit 1 of the present invention is used in conjunction with a deep oil reservoir of a four-cycle gasoline motor as shown in FIGURES 5, the tube 6 must be dimensioned to be open at the point where oil must be added to the oil level in order to provide proper protection to the motor. The tube 6 must be fitted so that the upper end of the nib 12 is just at the upper lowest point of the proper oil level. The tube 6 may be cut off at the end opposite the nib 12 or a new nib 12 cut into the tube 6 to adjust the proper length extending from inset 9. The tube may be cemented or if a good grip is had in the inset 9 the tube may be just inserted firmly.

In operation as the oil level in the deep reservoir of the four-cycle gasoline motor drops below the "add" point, air is permitted to seep into the tube 6 allowing oil to seep from the container 4 maintaining the oil level. The angu-

lation of the nib 12 permits the seepage whereas a flat end of the tube 6 might not permit such flow.

The terms and expressions which are employed are used as terms of description, it is recognized, though, that various modifications are possible within the scope of the invention claimed. 5

What is claimed is:

A kit for providing a visible oil level and reservoir for a four-cycle gasoline motor including a container through which oil may be viewed, means adapted to clamp said container to a selected element remote from said motor, an oil line, said oil line connected to said container, a convertible oil feed plug adapted to fit the oil inlet opening of a four-cycle gasoline motor, including means adapted to receive said oil line, a length within said plug adapted to 15 deliver oil to a shallow receptacle; said length opening into

the apex of a cone within said plug, and a removable delivery tube adapted to deliver oil to a deeper receptacle and adapted to be removably held by said length and extending through the enlarged exterior. 4
